UNITED STATES PATENT OFFICE.

SAMUEL C. PATTERSON, OF JUDSON, NORTH CAROLINA.

CYLINDER LOCK.

Application filed March 6, 1926. Serial No. 92,924.

This invention relates to improvements in a control mechanism and a lock therefor, which is more especially adapted for application to motor vehicles for controlling the power supply circuit from the battery.

The invention particularly comprehends improvements in the construction of locks and locking mechanism for adaptation in any form of lock construction, operating on an improved principle requiring a double operation of a key in more than one direction for releasing the locking mechanism for operation of the mechanism controlled thereby.

Another object of this invention resides in providing a key operated controlling mechanism for a lock which will require the position of the key in the mechanism by movement in two directions before the controlling mechanism can be released for the operation of the lock or other mechanism controlled thereby.

The invention further includes the provision of a lock controlled switch mechanism which is adapted to control the current supply circuit from the battery of a motor vehicle, in which the locking mechanism is mounted on the instrument board and provided with suitable connections with the switch mechanism mounted on or adjacent the battery so as to prevent tampering with the electrical mechanism of the motor vehicle under ordinary conditions.

The invention comprehends numerous other objects residing in the principle of operation of the locking mechanism and the construction and relation of the parts for carrying out this principle, which are more particularly pointed out in the following detailed description, and in the claims directed to a preferred construction, it being understood, however, that this invention may be applied to any form of lock controlled by a key without departing from the spirit and scope of the invention as herein set forth.

In the drawing forming part of this application:—

Figure 1 is a view of the locking device applied to the instrument board of a motor vehicle showing the arrangement of the ignition switch, battery and the lock controlled switch mechanism diagrammatically.

Fig. 2 is a vertical sectional view through the lock assembly and housing applied on the instrument board showing the locking cylinder in elevation.

Fig. 3 is a vertical sectional view taken on the line 3—3 of Fig. 2.

Fig. 4 is a vertical longitudinal section taken through the locking cylinder and adjacent parts, showing a key in position in the lock performing the first step in the operation of releasing the cylinder, and preparatory to the second step of operation for releasing the cylinder, on a substantially enlarged scale.

Fig. 5 is a vertical transverse sectional view through the locking cylinder taken on the line 5—5 of Fig. 4.

Fig. 6 is a transverse section taken on the line 6—6 of Fig. 4.

Fig. 7 is a vertical sectional view taken on the line 7—7 of Fig. 4.

Fig. 8 is a segmental sectional view illustrating the operating block for the locking rod of the cylinder as taken substantially on line 8—8 of Fig. 5.

Fig. 9 is a front elevation showing parts broken away of the locking mechanism showing the manner of applying the handle to the forward end of the cylinder by which it may be operated after releasing the locking devices with the key.

The instrument board of a motor vehicle is indicated generally at 1 which is provided as usual with the ignition control switch 2. The usual battery of the automobile is indicated at 3 and the starter button at 4.

This invention contemplates controlling the primary circuit 5 from the battery which leads to the various electrical apparatus of the motor vehicle and for this purpose provides a housing 6 which is mounted under the seat or floor board adjacent to the battery box in which are mounted a pair of stationary contacts 7 and a rotatable switch arm 8, adapted for engagement with the contact in one position to close the main circuit from the battery and in the other position to open said circuit to prevent operation of electrical apparatus on the automobile.

A pair of operating wires 9 are attached at one end to the switch blade 8 at opposite sides of the pivot thereof and slidably ex-

tend through the conduit 10 to the operating and control mechanism indicated at 11, the ends of the wires 9 being secured to the arms 12 mounted on the locking cylinder 13 of the control mechanism.

The control and locking mechanism includes a main housing section 14 of cylindrical form having a closed end 15 provided with a seat 16 in its central portion for receiving and rotatably supporting the end of the locking cylinder 13. This end wall 15 is also formed with rod recesses 17 for receiving the ends of the locking rods 18 slidably mounted in an axial plane in the cylinder 13. A bearing plate 19 is mounted in the forward end of the housing 14 and provided with a cylindrical bearing portion 20 receiving and mounting the locking cylinder 13 therein.

20 The instrument board 1 is formed with an opening through which the cylinder 13 extends. On the forward face of the instrument board surrounding the cylinder is mounted the escutcheon plate 21 while an 25 operating handle for the cylinder 22 is mounted on the forward end of the cylinder and which is received within the recess 23 formed in said handle. A suitable set screw or locking screw 24 as shown in Fig. 9 serves 30 to rigidly unite the operating handle 22 with the cylinder.

The locking mechanism of this invention includes the provision of a central axial bore through the locking cylinder 13 as indicated at 25 which receives the key guiding plug 26. This key guiding plug on its rear end is formed with an annular flange 27 seating in a correspondingly shaped recess in the rear end of the locking cylinder as shown in 35 Fig. 4, while substantially the entire length of the plug is bifurcated to provide a key slot 28 for slidably receiving the key 29. The forward end of this key plug extends beyond the forward end of the locking cylinder 13 and through an opening 30 in the handle 22 in a manner as shown in Fig. 2 so that the key may be slidably inserted from the forward end thereof through the slot in an axial direction in the cylinder.

50 The central portion of the outer periphery of the locking cylinder 13 is provided with arcuate recesses 31 in which extend the locking bolts 32 formed with bifurcated ends 33 for receiving the locking lugs 34 mounted 55 on the locking rods 18, which in one position of their sliding movement are adapted to be seated in the bifurcated end portion of the locking bolts 32 as shown in Fig. 4 for preventing rotation of the locking cylinder 13. 60 In this position of the locking rods 18, the ends thereof seat in the recesses 17 in the closed end portion 16 of the casing and co-operate to effectively lock the cylinder 13 against rotation.

65 The locking bolts 32 are carried by the

cylindrical bearing portion 20 of the bearing plate 19 and serve to limit the rotative movement of the locking cylinder in accordance with the size of the arcuate slots 31. The portions of the slot 31 adjacent to the 70 lugs 34 are enlarged as shown at 35 to permit the movement of the lugs in the unlocking operation of the cylinder by the key 29, which will be described.

A plurality of radially extending bores 75 36 are formed in the locking cylinder communicating with the bore 25 in the central portion thereof, and in which are mounted locking pawls 37 adapted for sliding movement in the radial bore and normally projected toward the axial bore 25 by suitable coiled springs 38. These locking pawls 37 are provided with shoulders 39 adapted to seat in the reduced diameters 40 of the locking rods 18 so that in seated position as 80 shown in Fig. 3, these pawls will prevent axial movement of the locking rods 18 and are moved by the key to the position shown in Fig. 4 for permitting the unlocking of the locking cylinder so that it may be subsequently operated for moving the wires 9 or a locking bolt as well as any other desired type of mechanism in the rotation of 85 said cylinder.

These locking pawls 37 are also provided 90 with laterally extending feet 41 which are adapted to seat in recesses 42 in locking position formed in the key guiding plug 26 so as to lock said key guiding plug against 95 rotation in the locking cylinder. These recesses are more clearly shown in Fig. 6.

Operating blocks 43 are mounted on the locking rods 18 as shown in Figs. 4 and 5, which are seated within the recesses 44 in the locking cylinder said recesses opening in 100 the axial bore 25 therein. The faces of these operating blocks 43 extend into recesses 45 in the key guiding plug wherein they are formed with diagonal key slots 46 which may be of any desired shape or construction 105 and which may be one or more in number such as shown in Fig. 8, where two of such slots are illustrated. These operating blocks are positioned in the locking cylinder 13 in 110 such a manner that in the position of the parts as indicated in the drawing which is the locked position of the mechanism, the blocks will have the edges formed with the key slots 46 terminating adjacent the key receiving slot 28 formed in the key guiding 115 plug 26.

The key 29 is formed with recessed edge portions 47 to provide operating extensions 48 projecting from these edges in a predetermined position for engagement in the key slots 46 of the operating blocks while at 49 the recessed edge portion of the key is formed with projections for engagement with the feet 41 of the locking pawls 37 in order that a properly constructed key placed in the slot 120 125 130

28 and turned will release the several locking devices so that the locking cylinder may be released for operation.

Figure 4 illustrates the key positioned in place to permit the release of the locking device as above described in which the projections 49 are shown in position and in engagement with the locking pawls 37, supporting said pawls in raised position so that the rods 18 may be moved axially upon a rotation of the key and the plug 26 through a limited movement governed by the length of the key slots 46 in which movement the projections 48 will slidably engage in the slots 46 of the operating blocks and due to the angular relation of said slots will produce an axial movement of the operating blocks in the recesses 44 so that the lugs 34 and the ends of the rods 18 will be moved out of engagement with the locking bolts 32 and the recesses 17. This will permit the release of all parts for an operation of the locking cylinder 13 by the operation of the handle 22.

The operation of the handle 22 will move the wire 9 through the movement of the arm 12 so that the switch blade 8 will be operated to close the circuit between the contacts 7.

From the above description, it will be seen that a locking mechanism has been provided requiring the movement of two cooperating and interlocking mechanisms through the operation of a single key which is required to have two movements for producing the total releasing of the locking parts for the cylinder in order to permit operation of the locking cylinder for the purpose to which it is adapted. In addition, the formation of the key guiding slot 28, the positioning of the locking pawls 37, and the operating blocks 43 together with the formation of the key slots 46 therein provide a plural combination of control elements for the lock with which the key must be operatively associated by which an endless combination of constructions may be provided in order that any number of locks may be constructed requiring separate keys for their operation.

The lock construction further tends to prevent the opening thereof with instruments other than a key designed to fit the lock in view of the fact that the operating block 43 is always concealed in the locked position of the parts from engagement through instruments inserted in the slot which might be used to operate the blocks in that the projecting portions are positioned to one side of the key slots 46 and require a relative movement of the plugs 26 in the

locking cylinder to obtain operation of the locking rods 18.

This rotation of the plug 26 is normally prevented by the locking pawls 37 seating in the recesses 42 in the plug.

With the construction above described, applied to a motor vehicle construction, with the switch member 8 controlled thereby, it will be seen that convenient operation and control over the electrical circuits of a motor vehicle may be obtained which will prevent tampering and unauthorized operation of the electrical apparatus operated by the ignition switch 2 or the starter button 4 from the battery.

Having thus described my invention, what I claim as new is:—

1. In combination, a support, a locking cylinder rotatable in said support, a key plug rotatable in said cylinder, movable locking means for locking the cylinder in the support against rotation, secondary locking means for locking the plug against rotation in the cylinder, said means and secondary locking means having interlocking cooperation with each other, and requiring a key of predetermined form movable in said key plug in two directions successively for unlocking both of the locking means successively from interlocking cooperation with each other and locking cooperation with the support permitting rotation of said cylinder in said support.

2. In combination, a support, a locking cylinder rotatable in said support, a key plug rotatable in said cylinder having a key slot formed therein to slidably receive a key of predetermined form, locking bars mounted for axial sliding movement in said locking cylinder for cooperation with the casing, said locking bars being mounted in parallelism with the key slot in said key plug, locking pawls in said locking cylinder to lock the key plug against rotation and having interlocking cooperation with said locking bars, the formation of said key being adapted to operate said locking pawls for releasing the key plug for rotation in the cylinder and unlocking said pawl from cooperation with the locking bars, and means operable by a limited rotation of the key plug and key therein subsequent to the unlocking movement of said pawls for producing an axial sliding movement of said locking bars to move said bars to unlocking position, permitting operation of said locking cylinder.

In testimony whereof I affix my signature.

SAMUEL C. PATTERSON.
